UNITED STATES PATENT OFFICE

151,772

DESIGN FOR A WATER SPRINKLER

Charles B. Kemp, Detroit, Mich.

Application October 26, 1946, Serial No. 134,283

Term of patent 7 years

(Cl. D91—1)

To all whom it may concern:

Be it known that I, Charles B. Kemp, a citizen of the United States, residing at Detroit, in the county of Wayne and State of Michigan, have invented a new, original, and ornamental Design for a Water Sprinkler, of which the following is a specification, reference being had to the accompanying drawing, forming part thereof.

The single figure is a perspective view of a water sprinkler, showing my new design.

The dominant features of the design reside in the portions shown in full lines.

I claim:

The ornamental design for a water sprinkler, substantially as shown and described.

CHAS. B. KEMP.
